UNITED STATES PATENT OFFICE.

JOHN B. PURVIS, OF DETROIT, MICHIGAN.

FOLDING BED.

1,264,879.

Specification of Letters Patent. Patented Apr. 30, 1918.

Application filed February 19, 1917. Serial No. 149,463.

To all whom it may concern:

Be it known that I, JOHN B. PURVIS, a citizen of the United States of America, residing at Detroit, in the county of Wayne 5 and State of Michigan, have invented certain new and useful Improvements in Folding Beds, of which the following is a specification, reference being had therein to the accompanying drawings.

10 This invention relates to folding beds and to an arrangement thereof that insures positiveness and ease of action in opening, compactness of design with possibility of use of the closed bed as a dresser, bookcase, or the 15 like and other features of advantageous construction which provide a structure of good appearance that is both light and strong.

The invention consists in the matters hereinafter set forth, and more particularly 20 pointed out in the appended claims.

In the drawings,

Figure 1 is a plan view, partially broken away and in section, of a bed that embodies features of the invention, in extended position;

Fig. 2 is a view in side elevation, partially broken away and in section, of the bed in extended position;

Fig. 3 is a view in perspective showing 30 the bed partially closed;

Fig. 4 is a view in detail showing the connection of side members of the bed with the head board;

Fig. 5 is a view in cross section of the bed 35 in fully closed position;

Fig. 6 is a view in side elevation showing a modification of the bed when extended, together with details of another type of operating device, and

40 Fig. 7 is a view showing the modification, of the operating device.

As herein indicated in preferred form, a headboard 1 with the usual corner posts, and with the upper portion either provided with 45 a mirror 2 or arranged as a bookcase or the like, is connected and held in parallel relation with a footboard 3 by side lazy tongs 4 and 5 and a horizontal set of lazy tongs 6 which lie below the spring rails of the members.

The side lazy tongs 4 and 5 are severally connected at their respective end portions by suitable pivot means directly to the corner posts 7 and 8, of the head, and corresponding members 9 of the foot board. The horizontal lazy tongs 6 are pivoted at one ex-

tremity 10 to a member 11 of the head board and at the other end by a pivot 12 to a corresponding transverse member 13 of the foot-board. The other head extremity 14 of 60 the lazy tongs 6 travels in a longitudinal slot 15 of the member 11, while the corresponding member 16 has a pin and slot connection indicated at 18 to the member 13. As a preferred form of extending device, a 65 crank arm 19 operates a shaft 20 that passes through a swiveled bearing 21 and has screwthreaded engagement with a nut 22 pivoted to the lazy tongs 6 at the pivotal junction of the cross members thereof, so 70 that the reciprocation of the nut when the shaft is rotated in either direction extends and retracts the lazy tongs in a familiar manner and thereby carries with it the remainder of the structure and opens or closes 75 the bed.

In order to maintain the bed in open position and prevent any possible collapse thereof, a pair of side rails are provided each consisting of a section 24 and a corresponding member 25 pivoted respectively to the head and foot boards, and provided with a lug 27 on the section 25 that overlies the section 24 when the rail is extended and thereby forms a rule joint which does not 80 break down and which locks the bed when once extended. The mattress or spring rails 28 on the head and 29 on the foot are arranged to carry any suitable spring mattress such as indicated at 30 that will collapse 90 and take the form indicated in Fig. 5, thereby giving plenty of space for the clothing or bedding. This space is further maintained by the use of brackets 31 to form the connections or pivot supports for the sections 24 of the side rails. The space above the lazy tongs is utilized by the insertion of drawers 32 and 33 in the foot board which is carried back with side panels 35 as indicated, to form a complete housing for the 95 mechanism of the bed when the same is collapsed.

If preferred, another form of operating mechanism may be used wherein a transverse shaft 36 with operating handle 37 carries a pair of small drums 38 and a larger central drum 39. Cables 40 are each connected to a quadrant arm 41 of one of the sections 24 and wound around one of the drums 38. The end portion of a cable 43 is 110 attached to the larger drum and then passed directly around a guide pulley 44 to a fasten-

ing device 45 on the head board. The drums are so proportioned in relation to each other that the cables are taut and by this arrangement any rotation of the shaft 36 by the 5 crank 37 projects or retracts the head and foot board to or from each other.

As a result of this construction, a folding bed is obtained that is a useful piece of furniture when in collapsed condition, is perfectly rigid and non-collapsible when extended, and that combines strength, lightness and surety of action with a construction that renders it sanitary and readily kept in order.

15 Obviously, changes in the details of construction may be made without departing from the spirit of my invention and I do not care to limit myself to any particular form or arrangement of parts.

20 What I claim is:—

1. A bed comprising a head board and a foot board maintained in parallel spaced relation by bottom and side lazy tongs, a shaft rotatable and longitudinally non-recipro-

cable in a bearing on one of the boards and 25 in screwthreaded engagement with a nut pivoted to lazy tongs at the middle joint thereof, and folding rails adapted to lock the boards in projected position.

2. A bed comprising a head board and a 30 foot board maintained in parallel spaced relation by bottom and side lazy tongs, a shaft rotatable and longitudinally non-reciprocal 35 in a bearing on one of the boards and in screwthreaded engagement with a nut pivoted to lazy tongs at the middle joint thereof, folding rails adapted to lock the boards in projected position, and a cabinet on one of the boards forming a housing for the bed when retracted and also an auxiliary piece of furniture.

In testimony whereof I affix my signature in the presence of two witnesses.

JOHN B. PURVIS.
